UNITED STATES PATENT OFFICE.

HOMER J. ROBERTS, OF EVANSTON, AND CYRIL A. SOANS AND ALBERT H. GRAVES, OF CHICAGO, ILLINOIS, ASSIGNEES, BY MESNE ASSIGNMENTS, TO HOMER ROBERTS TELEPHONE CO., A CORPORATION OF WEST VIRGINIA.

PARTY-LINE TELEPHONE SYSTEM.

No. 926,510.

Specification of Letters Patent.

Patented June 29, 1909.

Application filed January 8, 1907. Serial No. 351,296.

To all whom it may concern:

Be it known that we, HOMER J. ROBERTS, a citizen of the United States, residing at Evanston, in the county of Cook and State of Illinois, CYRIL A. SOANS, a citizen of the Kingdom of Great Britain, residing at Chicago, in the county of Cook and State of Illinois, and ALBERT H. GRAVES, a citizen of the United States, residing at Chicago, in said Cook county, Illinois, have invented certain new and useful Improvements in Party-Line Telephone Systems, of which the following is a specification.

This invention relates to improvements in party-line telephone systems, and refers more specifically to a selective lock-out system of the bridging type in which ringers responsive to differentiated current are effective to control the talking connections.

Among the salient objects of the invention are to provide a system in which the ordinary bridging method of arranging the line wires may be employed in conjunction with sub-stations embodying both selective signaling and lock-out or privacy connections; to provide in such a system lock-out connections at each sub-station controlled by a corresponding relay which is in turn controlled by the operation of the ringer or other signaling device, whereby the simple operation of throwing that particular kind of current upon the line effective to operate the ringer of the particular station wanted, automatically operates the relay of that station and cuts in the party wanted; to provide in a system of the general character described means whereby the simple act of signaling for a connection on the part of the subscriber operates to lock out all other parties on the same line; to provide in such a system means enabling the locked out subscribers to at all times send in an emergency calling signal; to provide a system so organized that the subscribers' stations are each and all at all times under the complete control and supervision of the central operator; to provide a system so organized that two or more parties on the same line can be given talking connections to the exclusion of all other parties and in which also the restoring of the entire line to normal is accomplished by a single operation whether one or more parties have been given talking connections;

to provide a system of the character described which embodies independent calling in and clearing out signal systems; to provide a system in which the talking circuits are full metallic and free from external grounds; to provide a system particularly adapted to common battery practice, although, in its broader sense, not limited to this type; to provide a system characterized by extreme simplicity of manipulation, both on the part of the exchange operator and the subscribers, and therefore susceptible of being handled with great rapidity; to provide a system so organized that the several sub-stations are in no sense interdependent; to provide a specific embodiment of the system in which harmonic ringers are employed; to provide a system so organized that it is impossible for a subscriber to tie up the line or interfere with the exchange operator's manipulation of the same without deliberately disorganizing his set; and in general to provide a simple and practical system of the character referred to.

To the above ends the invention consists in the matters hereinafter described, and more particularly pointed out in the appended claims.

In the accompanying drawings—Figure 1 is a view showing diagrammatically the central exchange and sub-station apparatus and circuit connections; Fig. 2 is an elevation of the lock-out relay; Fig. 3 is a top plan view of the same with a portion of the biasing bar broken away; Fig. 4 a sectional detail of the contact group of the lock-out relay; Fig. 5 an elevation of the harmonic ringer, parts being broken away, and Fig. 6 a top view of the ringer, with parts broken away.

The preferred embodiment of the system shown herein is one in which harmonic ringers are employed at the several sub-stations, responsive, as usual, to alternating current of different frequencies, and these ringers are bridged across the line, but, as intimated in the statement of the objects of the invention, the system is not limited to this specific embodiment.

Describing first the circuits and apparatus as they are shown conventionally in the diagram, A and B, respectively, designate as a whole the sub-stations, C the spring jack, D the line relay, and E, E', the respective

halves of the cord circuit and associated apparatus. Associated with the calling end of the cord circuit are a plurality of keys, as 1, 2, 3, 4, one corresponding to each sub-station, and these keys in turn control corresponding devices, 5, 6, 7 and 8, affording the several different frequencies of current required; the devices shown in this instance being alternators. Associated with each end 10 of the cord is also a restoring key, as 9 and 10. There is also connected with the cord an operator's listening key 11 and a differentially wound signal relay 12. Other accessories of the central exchange will be described in connection with the description of 15 the circuits.

Describing now more particularly the sub-station apparatus and circuits, it is to be noted that all sub-stations are precisely alike, 20 with the exception that the several ringers are, of course, so modified in the usual way as to respond only to current of proper frequency. In the diagram 13 designates as a whole the ringer, the windings of which are 25 bridged across the drop wires L' and R', as usual. Mounted upon a vibrating part of the ringer, the armature as shown is a contact device 14 connected by conductor 15 with drop wire R'. A co-operating back 30 contact 16 is connected by a conductor 17 with the switch spring 19 of a lock-out relay designated as a whole 18. This relay is in its general construction similar to an ordinary polarized magnet comprising the usual 35 spools 20, 20', co-operating armature 88, biasing bar 87, and frame work (not shown in the diagram). Upon the frame work is mounted a spring latch 23 (hereinafter more 40 specifically described) which normally holds the switch spring 19 depressed and in contact with a bottom spring 24; the latter being connected with one side of the receiver 25 by a conductor 26. When released from the latch the switch spring rises and closes 45 contact with a top spring 27 which is connected by a conductor 28 with drop wire R'. Switch spring 19 is also connected by a conductor 29 with a cam spring 30 which is actuated mechanically by the switch-hook 31 50 and said switch hook serves to momentarily force spring 30 into contact with a spring 30' connected to ground at 32. Normally the switch-hook rests in engagement with a grounding spring 33 connected to ground as 55 indicated at 34'. As the switch-hook rises, upon removal of the receiver therefrom, it leaves spring 33 and closes with a top spring 34 here connected by a conductor 35 through the transmitter 36 to drop wire L' and momentarily establishes a flash ground circuit 60 through the relay 18 and to a corresponding ground at "central." This circuit is as follows: From ground at 32, through springs 30' and 30, conductor 29, windings of the relay 18 connected with conductor 29, thence

by a conductor 37 to switch-hook, to spring 34, conductor 35, left drop wire L', left main line L, and to and through line relay D. Describing the circuits of the latter instrument, a conductor 38 permanently connected 70 with L leads to a bottom spring 39 of the relay, which spring normally engages the center or switch spring 40 thereof. The latter is connected by a conductor 41 with a back spring 42 normally closed upon and co-operating 75 with a contact 43 carrying but insulated from the tip spring 44 of the spring jack. Spring 43 is connected by a conductor 45 with the windings of relay D, and the latter by a conductor 46 with one side of a 80 battery 47. The opposite side of this battery is grounded, as indicated at 48.

The circuit from L through 38, 39, 40, 41, 42, 43, 45, and the windings of the relay and battery to ground completes the flash ground 85 circuit from the sub-station, and closes the relay D, and at the same time operates the lock-out relay to trip off the latch spring 23 thereof; the latter effect being accomplished by a cam extension upon the end of the 90 armature 88 engaging the inclined overhanging part 23' of the latch spring, as more fully described in connection with the description of the construction of said relay hereinafter to follow. The operation of relay D and lock-out relay 18 accomplishes three 95 distinct ends, viz: The relay D disconnects the battery 47 from the line and lights a signal lamp, and the relay 18 establishes talking connections at the subscriber's set. 100 The opening of circuit between 39 and 40 at relay D disconnects the battery from line and at the same time establishes a holding circuit between switch spring 40 and the top spring 49 which is connected by a conductor 50 through a signal lamp 51 to the 105 grounded side of the battery. This holding circuit is maintained until the operator plugs in, whereupon the movement of tip spring 44 opens said circuit between contacts 110 42 and 43.

The talking circuit connections established by the operation of relay 18 are from drop wire L' over conductor 35, through transmitter 36, spring 34, switch-hook 31, conductor 115 37 to a branch conductor 52, condenser 53, to one side of the receiver 25, and from the latter by a conductor 54 to conductor 17, from the latter through switch spring 19, top spring 27 and conductor 28 to drop wire 120 R'. It will be noted that normally the receiver is short circuited, but that upon the movement of switch spring out of engagement with bottom spring 24 this short circuit is opened.

After relay D has operated and before "central" has plugged in, it is obviously impossible for any other subscriber to secure a talking connection for the reason that there is no battery on the line by means of 130

which his lock-out relay could be tripped. As soon as the operator answers by plugging in the answering end E of the cord circuit, a battery, designated 55, is connected to line, 5 but this battery is so arranged as to make it impossible for a second party to automatically obtain talking connections, as will hereinafter appear. Battery 55 furnishes talking current and is arranged in a way familiar to those skilled in this art, being connected between a pair of "split" repeating coils 57, 57', and one side of the battery, the positive, being grounded, as indicated at 10 58. With battery 55 to line, it will be seen that a flash ground established at any other station than that of the party having talking connections, will induce a flow through his lock-out relay in a direction opposite that which is required 15 to trip it off. That is to say, the flow will be from ground 32 at his station by way of conductor 28' through his lock-out relay by way of his switch hook connections to left main line over the latter to the metallic 20 bridge then existing at the subscriber's set who has been given talking connections, through the latter's set including switch hook connections and the lock-out relay at that station (current through the latter relay 25 being in the proper direction to keep it tripped off) to the right main wire and thence to the sleeve side of the cord circuit, to and through battery 55 and to ground 58. The attempt to secure connection will therefore be ineffective. However, the circuit 30 last described is made use of to transmit a calling in signal to "central" so that the operator may be apprised of the fact that another subscriber desires connection, and may, 35 if she so desires, take the line away from the busy party and make such connection. This is accomplished through the differential relay 12. This relay comprises a magnet having two windings wound oppositely upon 40 the same core, as indicated in the diagram, each winding being included in the corresponding side of the cord circuit.

The armature of the magnet operates to close a lamp circuit at two contact springs 50 59 and 60; said lamp circuit being connected to the opposite sides of battery 55 and including a lamp 61, as shown clearly in the diagram. Current flowing over one side of the line only, as it does in the case of the flash 55 ground circuit described, obviously operates relay 12 and momentarily lights the lamp. If it be understood that the repeated moving of the switch-hook up and down indicates an emergency call, it will be obvious 60 that the resultant flashing of the lamp at "central" would induce the operator to give the desired connection. In this connection it may be noted that when the subscriber who has talking connections finishes his 65 conversation and returns his receiver to the

switch-hook, by so doing he places a continuous ground upon the line through the bottom spring 33 and this causes the lamp 61 to glow continuously and so forms a clearing out signal. This last circuit is from ground 70 at 34', through spring 33, switch-hook 31, conductor 37, windings of relay 18, switch spring 19, top spring 27, conductor 28, drop wire R' and thence to "central" over right main line. It will be noted that the current 75 flow through the subscriber's relay 18 is in a direction opposite that which would restore his relay, and accordingly he may attract the attention of "central" by moving his switch-hook up and down without thereby 80 losing his talking connection, in an obvious manner. To connect a party who has thus called in with a given party upon another similar line, the operator simply plugs in the opposite end E' of the cord and then closes 85 that one of the ringing keys, 1, 2, 3 or 4, corresponding to the party desired, thereby throwing on ringing current from the corresponding alternator and selectively ringing the called party's bell. The metallic 90 circuit which effects the ringing is the usual and obvious circuit, and need not be traced, it being noted, however, that the ringing is effected in this instance, as is often done, through a condenser 62 at the sub-station. 95

The ringing of a subscriber's bell closes a circuit through his relay which trips the latch of the latter and gives him talking connections as follows: Upon a vibrating part of each ringer, the armature as shown in the 100 present instance, is mounted a yieldable spring contact 14, connected to the right drop wire by conductor 15, as hereinbefore mentioned. Upon the frame of the ringer is mounted a stationary but adjustable contact screw 16 which co-operates with the tip of spring 14 and is connected to switch spring 19 by conductor 17, as already described. These contacts are so adjusted as to close only when the ringer is thrown into 105 full vibration and the clapper thereof actually makes contact with the gongs, thereby avoiding the closing of the circuit controlled by these contacts by the false or semi-vibrations common to harmonic ringers. 110

Connected with one side of the calling end of the cord, at "central," is a grounded battery 63, the connection being through a conductor 64 having branch wires 65, 66, 67 and 68, leading to the corresponding outer spring 120 on the same side of each ringer key. These branch wires are each also connected to one brush of the corresponding alternator, while the opposite brushes are respectively connected to the corresponding outer springs at 125 the opposite sides of the keys by conductors, as 69, 70, 71 and 72. Accordingly whenever a ringer key is closed and the corresponding ringer is in vibration a ground to ground intermittent current will be established from 130

battery 63 through the corresponding lock-out relay at the sub-station being called; this circuit being from ground at battery 63 over the sleeve or right side of the cord and over the right main wire and corresponding drop wire to contact spring 14, thence over conductor 17, to and through the relay, and by conductor 37 to the switch-hook and to ground through the bottom spring 33. These 5 intermittent current impulses operate the armature of the relay and trip off the latch, as hereinbefore described. In this connection it may be noted that the intermittent impulses, though extremely brief, are effective for the reason that the armature of the lock-out relay is unrestrained in that movement which trips the latch until it encounters the latter, and the momentum of the armature is effective in disengaging the 10 latch even with the highest rate of frequency now used in harmonic ringing. Moreover, it will be noted that the higher the rate of frequency the more certainly will the successive impulses increase the momentum of the armature to do the necessary work, while as to the lower frequencies the 15 interval of contact is long enough to insure effective operation by a single contact. The talking connections established by thus 20 "ringing on" are, of course, the same as those hereinbefore described as secured by the calling in subscriber. It will be noted that battery 63 has that pole thereof to line which is 25 opposite in polarity to the battery which 30 operates the relay over the left limb, and hence operates the relay in the right direction.

Emergency signals and clearing out signals are sent in from the line with which 40 the calling end of the cord is connected in precisely the same manner as in the case of the line with which the answering end is connected, and for this purpose the relay 12' is interposed in this end of the cord and 45 controls a lamp circuit including a lamp 61' arranged in precisely the same relations to battery 55 as is the lamp 61 and its circuit. Occasionally it is necessary, of course, to put two or more parties upon the same line 50 in talking connection with each other. This is accomplished by first taking the order of the party who calls in and thereby automatically secures talking connections, then withdrawing the answering plug and inserting 55 the calling plug, and proceeding to select the called party precisely as though he were upon another line. It is to be noted that the calling party must be instructed to momentarily hang up his receiver while the 60 wanted party is being rung on in case such party be upon the same line with himself. This precludes any disarranging flow of current through the calling party's station.

To restore the lines to normal the two 65 clearing keys 9 and 10 are interposed in the

respective ends of the cord circuit and control a battery 73 which is desirably of somewhat higher voltage than the other batteries described, to insure an ample flow of current notwithstanding several sub-stations 70 may be bridged on, *i. e.*, have been given talking connections, so as to restore simultaneously. The negative side of battery 73 is grounded at 74 and this side of the battery connected by conductors 75, 75', with 75 normally open springs on the tip sides of the respective restoring keys 9 and 10. Similarly the positive pole of the battery is connected by conductors 76 and 76' to the open springs of the restoring keys at the sleeve 80 sides thereof. Accordingly when either key 9 or 10 is closed, and assuming that the party or parties having talking connections have returned their receivers to their switch-hooks, simultaneous metallic and ground 85 to ground circuits are established which flow through the lock-out relays in the proper direction to latch them up or restore them to normal. At the exchange end, these circuits are obvious. At any 90 given sub-station the grounded circuit will be from the right drop wire over conductor 28, springs 27 and 19, conductor 17, through the windings of the relay, conductor 37, switch-hook 31, spring 33 and ground 34. 95 The mechanism of the relay is so organized that the circuit through its contact springs 27 and 19 is maintained until the relay becomes deenergized. Should any part who has talking connections neglect or refuse to 100 hang up his receiver so as to establish the ground at 34, the metallic circuit from battery 73 is effective to restore the relay. This circuit at the sub-station is from the left drop wire through conductor 35, top spring 105 34, switch-hook 31, conductor 37, windings of the relay, conductor 17, switch spring 19, top spring 27 and conductor 28 to the right drop wire and is of the proper polarity to 110 restore the relay. This latter circuit is, of course, the circuit utilized to take the line away from an arbitrary or careless subscriber who attempts to hold the line too long or neglects to hang up the receiver after he is done talking.

The two main instruments at each sub-station, *viz*: the ringer and the relay will now be described: The ringer is a well-known make of harmonic instrument, being a polarized instrument having the usual heel piece 77, biasing bar 78 connected with the heel piece, and at its opposite end bearing against a pair of iron or steel blocks 79 clamped between the two members 80, 80', of the yoke and in turn clamping and holding a flat leaf spring 81 upon which the armature 82 and clapper-stem 83 are suspended. Each clapper-stem carries a clapper-weight 84 of adjusted weight corresponding to the frequency it is intended to respond 115 120 125 130

to. Upon one of the spool heads is mounted a bracket 85 through which is adjustably threaded the contact screw 16 referred to in the diagrammatic view, and upon the corresponding end of the armature is mounted the insulated yielding spring 14. The relay 18 is also a polarized magnet having the usual heel piece 86, biasing bar 87 connected therewith and overhanging the armature 88, yoke 89 mounted upon the spools and carrying the armature, and the group of three springs, 19, 24 and 27, hereinbefore described.

The armature is provided with a right angled arm or extension 90 which overlies the group of springs, and in this extension is inserted an insulating bushing 91, in which in turn is mounted a head pin 92. The head of the bushing projects slightly below the armature that engages the top spring (see detail Fig. 4). The head of the pin 92, in the upstroke of the armature, engages the inclined portion 23' of the spring latch 23 and forces outwardly the latter. This spring latch is mounted upon a downturned extension 89' of the yoke and insulated from the latter. Below the inclined latch lip 23'' is formed a stop lip 23° which projects outwardly beyond the latch lip and forms a stop to arrest the downward movement of the switch spring under the action of the armature. The purpose of this stop is to prevent sparking and consequent momentary interruption of the circuit between the top spring and switch spring during the latching movement. An insulating spacing bushing 93 is mounted in the bottom spring 27, extends through an opening in the switch spring and engages the top spring. The tension of the bottom spring is upward, and when the group is unlatched insures the closing of contact between the bottom and switch springs.

We claim as our invention:

1. In a party line telephone system, the combination with a line wire extending through a plurality of substations, means for sending differentiated current over said line wire and a selectively responsive ringer at each substation, of a lock out relay at each substation, contact mechanism actuated and controlled by said relay, talking circuit connections including said contact mechanism, and controlling connections between the ringer and relay of each substation, whereby the operation of the relay is controlled through the ringer.

2. In a party-line telephone system, the combination with a line wire extending through a plurality of sub-stations, means for sending differentiated current over said line wire and a selectively-responsive ringer at each sub-station, of a lock-out relay at each sub-station, talking-circuit connections controlled by said relay, a manually operable

switch and circuit connections between the switch and relay of each sub-station, whereby the operation of the switch controls the operation of the lock-out relay.

3. In a party-line telephone system, the combination with a line wire extending through a plurality of sub-stations, means for sending differentiated current over said line wire, and a selectively-responsive ringer at each sub-station, of a lock-out relay at each sub-station, contact mechanism actuated and controlled by said relay, talking circuit connections including said contact mechanism and electrical contacts and suitable circuit connections between the ringer and relay of each sub-station, whereby the operation of the ringer controls and initiates the operation of the relay.

4. In a party-line telephone system, the combination with a line wire extending through a plurality of sub-stations, means for sending differentiated current over said line wire, and a selectively-responsive ringer at each sub-station, of a polarized lock-out relay at each sub-station, talking-circuit connections controlled by said relay, and electrical contacts and suitable circuit connections between the ringer and relay of each sub-station, whereby the operation of the ringer controls and initiates the operation of the relay.

5. In a party-line telephone system, the combination with a pair of line wires extending through a plurality of sub-stations, means for sending differentiated current over said line wires, and a selectively-responsive ringer at each sub-station, of a lock-out relay at each sub-station, talking-circuit connections controlled by said relay, electrical contacts and suitable circuit connections between the ringer and relay of each sub-station, and means for establishing simultaneously a metallic circuit current flow through one of said instruments and a ground to ground circuit flow through the other.

6. In a party-line telephone system, the combination with a pair of line wires extending through a plurality of sub-stations, means for sending differentiated current over said line wires, and a selectively-responsive ringer at each sub-station, of a lock-out relay at each sub-station, talking-circuit connections controlled by said relay, electrical contacts and suitable circuit connections between the ringer and relay of each sub-station, means for establishing a metallic circuit alternating current flow through said ringer, and a ground to ground current flow through said relay.

7. In a party-line telephone system, the combination with a line wire extending through a plurality of sub-stations, means for sending differentiated current over said line wire, and a harmonic ringer at each sub-station, of a lock-out mechanism at each

sub-station, talking-circuit connections controlled thereby, and operative connections between the harmonic ringer, and lock-out mechanism whereby the latter is controlled 5 through the former.

8. In a party-line telephone system, the combination with a pair of line wires extending through a plurality of sub-stations, means for sending alternating currents of 10 different frequency over said line wires, and a harmonic ringer at each sub-station, of a lock-out relay at each sub-station, talking-circuit connections controlled by said relay, a pair of contacts carried by the ringer, one 15 moving with the vibrating part of the ringer

and the other relatively stationary and arranged in coöperative relation with the vibrating contact, circuit connections extending from one of the line wires through said contacts, through said relay and to ground, means for grounding the line at "central," and a source of current interposed in said grounded circuit. 20
